HYDRAULIC PISTON RING EXPANDER AND
PISTON HEAD COOLING DEVICE

Joseph L. Ippolito, Ansonia, Conn.

Application February 1, 1944, Serial No. 520,676

8 Claims. (Cl. 309—24)

1

This invention relates to a hydraulic piston ring expander and piston head cooling device for power pistons, particularly for the pistons of internal combustion engines, and has for an object to provide an improved means for expanding the piston rings and controlling their pressure against the walls of the cylinder and against the sides of the ring grooves, and which will form an effective means for cooling the head or end wall of the piston to reduce detonation knock and cause cooler running of the piston and piston rings.

Another object is to provide an improved means for circulating a cooling liquid against the head or end wall of the power piston to control the temperature thereof and produce cooler running of the piston and the rings carried thereby and to prevent or greatly reduce detonation knock.

A further object is to provide such a device which may be connected with the oil-pressure circulating system of the engine to be supplied with oil under pressure therefrom, both for the cooling effect of the piston and the expanding of the rings.

This invention is a further development and improvement on the invention of my prior Patent No. 2,282,475, issued May 12, 1942, for Piston ring expander.

With the foregoing and other objects in view I have devised the construction illustrated in the accompanying drawing forming a part of this specification. It is, however, to be understood the invention is not limited to the specific details of construction and arrangement shown but may embody various changes and modifications within the scope of the invention.

In the drawings:

Fig. 1 is a vertical section through a piston of an internal combustion engine and a portion of the cylinder with the cylinder head removed, and showing my improvement applied to the piston;

Fig. 2 is a plan view of one section of the cooling and pressure chamber removed and on a reduced scale;

Fig. 3 is a side elevation thereof;

Fig. 4 is a longitudinal section with a connection for a pressure supply conduit to the pressure and cooling chamber showing a nonreturn valve therein;

Fig. 5 is a longitudinal section through the outlet valve from the chamber;

Fig. 6 is a longitudinal section through a restrictor that may be used in the pressure supply conduit;

2

Fig. 7 is a section similar to Fig. 1, showing a modified arrangement;

Fig. 8 is a longitudinal section of the wrist pin of Fig. 7, and

Fig. 9 is a section of the upper end of the piston of Fig. 7 taken at right angles to the plane of Fig. 7 and substantially on line 9—9 of this figure.

Fig. 1 shows a portion of a cylinder 10 of an internal combustion engine having the usual cooling or water jacket 11. Mounted to reciprocate in the cylinder is the piston 12 including a head or end wall 13 and a skirt or side walls 14. In the side walls are one or more grooves 15 for expandable piston rings 16. Any usual number of grooves or rings may be used, three being shown in the drawing, the rings expanding to engage the side walls of the cylinder to prevent leakage of gas pressure past the piston, as is well known. Connected to the piston is the usual connecting rod 17 connected with the crank shaft (not shown) in the usual manner and connected to the piston with the usual wrist-pin 18.

Within the piston at the inner side of the head or end wall 13 is a pressure and cooling chamber 19. It is preferred that the upper part of this chamber be formed by walls 20 integral with the head 13 (although they could be part of a separate member secured to the head) and that the lower portion of the chamber be formed by a separate member 21. The side walls 20 and the side walls 22 of the member 21 are provided with flanges 23 fitting together and clamped together by suitable bolts (not shown) passing through suitable openings 24 in the flanges. In the construction shown these flanges also are provided with tubular extensions 25 together providing a cylindrical chamber 26 to receive pressure cylinders 27 which may be secured in position by external flanges 28 seating in grooves 29 in the flange wall. These cylinders are open at their inner ends so as to be in communication with the pressure chamber 19 and each encloses a piston 30 connected by a piston rod 31 passing

45 through an opening in the outer end of the cylinder where it is connected to a cross rod 32. Connected with this cross rod are pins 33 passing through openings in the side walls of the piston to the ring grooves 15. In each groove is a pair 50 of rings 16 which are split rings and tend to expand radially to engage the side walls of the cylinder in the usual manner. They are also separable vertically and each pin 33 has a tapered end 34 engaging between the two rings so 55 that as the pin is forced outwardly or radially by

action of the piston 20 it tends to expand the rings 16 radially to press them against the walls of the cylinder 10 and also tends to separate the two rings and press them respectively against the top and bottom walls of the groove 15 so as to prevent leakage of gas around the ring in the groove as well as past the grooves between them and the walls of the cylinder. The pistons 30 and the expanding rings are the same as disclosed in my prior patent above noted.

Connected with one side of the chamber 19 is a fluid pressure conduit 35 connected with the oil pressure circulating system of the engine. If the connecting rod 17 is drilled for an oil passage as indicated at 36, this conduit may be connected to this oil passage to receive the circulating oil under pressure therefrom. It may be connected to the piston rod by any suitable means, such for example as the fitting 37 and is connected to the chamber 19 by a suitable fitting 38. In this latter fitting is a check or nonreturn valve 39, which will permit flow of oil under pressure to the chamber but prevent its flow backward through the conduit. This valve is held in normally closed position by a suitable spring 40 pressing against the valve at one end and a suitable adjusting sleeve or nipple 41 at the other end, threaded into the valve casing. By adjusting this nipple in or out, the pressure of the spring 40 on the valve may be adjusted to adjust the pressure at which the valve will open. This fitting 38 is connected to the chamber in a horizontal position so that movements of the piston will not affect opening or closing of the valve, and there may also be in the conduit 35 a restrictor 42 having an outlet nipple 43 with a restricted passage 44 leading to the conduit. By using nipples with different sized passages the restriction may be made anything desired to maintain proper flow and pressure. The conduit 35 may be a flexible conduit to compensate for the slight rocking motion between the piston and the connecting rod 17, or if the connecting rod is not drilled it could be a conduit secured along the side of the connecting rod and connected with the oil pressure system. Instead of a flexible conduit a swivel joint or a universal joint could be used to compensate for the relative movements.

Spaced from the inlet connection 38 and preferably located at the opposite side of chamber 19 is an outlet 45. This is shown as a spring pressed ball valve 46 normally held closed by the spring 47 and having an outlet 48 for passage of the oil when the valve opens. At the opposite end it engages an adjusting nipple 49 which is screwed into the fitting 45 and may be adjusted to vary the tension of the spring to vary the pressure at which the valve opens and thus control the pressure in the chamber 19. After adjustment the nipple 49 may be held in the adjusted position by a simple locking means, such for example as a cotter pin 50. With this arrangement oil circulates through the chamber 19 and cools the end wall 13 of the piston. To improve this cooling effect baffle means is preferably provided in the chamber to direct the circulating oil toward or against the end wall. In the present case a transverse baffle 51 extends upwardly from the bottom wall of the chamber and in front of the inlet 38 and is preferably inclined toward and over this inlet, but is spaced at its upper edge from the end wall 13 so that the oil circulating from the inlet 38 is directed upwardly toward and against the head 13 as indicated by the ar-

rows as it passes through the chamber to the outlet 45. This outlet 45 is preferably arranged horizontally so that the valve is not affected by the movements of the piston.

5 In operation the oil under pressure from the oil pressure circulating system flows through the conduit 25 from the hollow connecting rod, or tube secured along the outside of the connecting rod, and through the restrictor 42, which will restrict the flow to the proper amount, and through 10 the nonreturn or check valve 39 to the chamber 19 where it is directed upwardly by the baffle 51 toward and against the head or end wall 13, thereby picking up a great amount of heat which 15 is carried out by the oil through the outlet valve 46 in the side of the chamber. This valve is a pressure valve and controls the pressure in the chamber 19. In conventional pistons the heat from the explosive charge on top of the piston 20 has to be conducted by the head or end wall 13 to the edge or side walls of the piston and the piston rings and then to the cylinder walls. As 25 the cooling effect at the center of the head depends on the conduction of the heat from this point through the walls as indicated it will be apparent that the head is not properly cooled. With the present construction, however, the head is cooled by the circulation of oil through the chamber 19 which picks up the heat so as to keep 30 the head and piston much cooler and thus eliminating or greatly reducing detonation knock which will enable engineers to raise compression on the engine and secure greater efficiency and better operation. This arrangement also gives 35 cooler running rings because the oil picks up a large amount of heat from the piston head which would otherwise be conducted to the rings. This reduces burning of the lubricating oil. The cooling liquid is also used to operate the expanding 40 means for the ring and therefore rings can be used with relatively low tension or pressure, say for example about two pounds. The hydraulic pressure means from the pistons 30 may be used at any additional pressure desired, usually about 45 twelve or thirteen pounds, so that the rings will have a pressure of say about fifteen pounds against the cylinder walls. Also with this arrangement wear on the rings is automatically taken up and the tapered pins 33 act on the double 50 rings as above described which forms a seal at the top and bottom of the grooves as well as against the walls of the cylinder. It will be evident that the pressure of the rings against the cylinder wall can be adjusted to any desired 55 amount depending on the pressure within the chamber 19 which may be adjusted by adjustment of the outlet valve 46.

In the forms shown in Figs. 7, 8 and 9, the pressure operated means for expanding the piston 60 ring is omitted, but the means for cooling the piston and particularly the piston head is retained. In the form shown in Fig. 1 the pressure operated means for expanding the piston ring may be omitted, using only the piston cooling 65 means. In Fig. 7, although the piston cooling means is substantially the same as that in Fig. 1, the cooling medium is conducted to the piston in a somewhat different way. In this arrangement the piston is shown at 51 in the cylinder 10 and has the usual expanding ring grooves in which are mounted the usual expanding rings 52. The piston is made hollow and at the inner side of the head 53 is the cooling chamber 54 corresponding to the cooling chamber 19 of Fig. 1. 70 75 This chamber is preferably formed in two parts,

the upper portion 55 being integral with the piston and the lower portion 56 being secured to the portion 55 by any suitable means, such for example as welding or screws, not shown but corresponding to the screws used in the openings 24 in flanges corresponding to the flanges 23 shown in Fig. 2. At one side of the chamber 54 is mounted the inlet valve 39 mounted in the fitting 38 the same as in Fig. 1, this being a check or nonreturn valve as described in connection with Fig. 1. On the opposite side of the chamber is the outlet 45 including the spring pressed valve 46 the same as described in connection with Fig. 1. This valve is adjustable the same as previously described to adjust the pressure of the spring 47 and therefore the pressure in the chamber 54. Between the inlet 38 and the outlet 45 is preferably provided a baffle 57 to direct the oil or liquid entering through the inlet 38 upwardly toward the head 53 of the piston to insure proper cooling of this head.

To further facilitate cooling and transfer of heat from the piston head to the circulating oil a series of integral ribs 58 are provided on the inner wall of the head projecting into the chamber 54. They are preferably arranged longitudinally of the direction of flow of the cooling oil so as not to pocket this oil or interfere with its circulation through the chamber. Ribs 59 may be provided outside the chamber on the portion of the head between the chamber and the side walls of the piston to help cool the piston by the oil splashed up into it during operation.

The circulating oil is conducted to the inlet 38 by a conduit 60. This corresponds to conduit 35 of Fig. 1 and may be connected to the oil passage 36 in the piston rod 17, the same as in Fig. 1, or it may be supplied with this circulating oil as shown in Fig. 7. In a similar way the conduit 35 in Fig. 1 may be provided with oil in the manner shown in Fig. 7. In this construction the wrist pin 61 is provided with a longitudinal passage 62, which is in communication with passage 36 in the connecting rod. For this purpose a circumferential groove 63 is provided in the wrist-pin in alignment with passage 36 with one or more transverse openings 64 leading from this groove to the passage 62. Spaced longitudinally from this groove 63 the pin is provided with another groove 65 communicating with the passage 62 by transverse drill 66, and the tube 60 communicates with this groove 65 as shown. This forms a direct communication from the passage 36 to the conduit 60, and a passage 36 is in communication with the oil pump or pressure circulating system as previously described the oil under pressure is supplied to the chamber 54 and circulates therethrough the same as described in connection with the device of Fig. 1. The ends of the passage 62 in the wrist-pin may be closed by plugs or caps 67, and they may be secured by a drive fit of a stem 68 in the end of the passage or they could be threaded in the passage. To prevent leakage of the oil past the wrist-pin annular grooves may be provided in the bored openings in the piston and the head 69 of the connecting rod in which may be mounted fiber or other packing 70. This construction and arrangement operates the same as that shown in Fig. 1 and as described in connection therewith except that the pressure operated piston ring expanding means is omitted.

Having thus set forth the nature of my invention, what I claim is:

1. A power piston of the character described

having an end wall and side walls, one or more ring grooves in the side walls, expandable rings in said grooves, an oil chamber within said piston at the inner side of the end wall, pressure means operated by oil pressure in said chamber and connected with the rings to expand the rings, and means for circulating oil under pressure through said chamber and against the end wall to operate said pressure means and cool the end wall.

2. A power piston of the character described including a head or end wall and side walls, ring grooves in the side walls, expandable rings in said grooves, an oil chamber within the piston at the inner side of the head or end wall, pressure means operated by oil pressure in said chamber and connected with the rings to expand the rings, a nonreturn valve connected with one side of the chamber, a conduit connected with said valve to supply oil under pressure to said chamber, and an outlet valve at the opposite side of the chamber to permit circulation of oil through the chamber to cool the head or end wall and operating against a spring to control the pressure in the chamber.

3. A power piston of the character described including a head or end wall and side walls, ring grooves in the side walls, expandable rings in said grooves, an oil chamber within the piston at the inner side of the head or end wall, pressure means operated by oil pressure in said chamber and connected with the rings to expand the rings, a conduit connected to one side of the chamber to conduct oil under pressure thereto, a restricted outlet at the opposite side of the chamber to permit flow of oil through the chamber to control the temperature of the head or end wall while controlling the pressure in the chamber and to retain the oil in the chamber when the piston is not operating, and a baffle

40 between the inlet and outlet extending upwardly from the bottom of the chamber toward the head or end wall and spaced therefrom to direct the flow of oil through the chamber to the head or end wall.

4. A power piston of the character described including a head or end wall and side walls, ring grooves in the side walls, expandable rings in said grooves, an oil chamber within the piston at the inner side of the head or end wall, pressure means operated by oil pressure in said chamber and connected with the rings to expand the rings, a conduit connected to one side of the chamber to conduct oil under pressure thereto, a nonreturn valve in said conduit adjacent said chamber, an outlet valve spaced from said inlet and capable of restricting flow of liquid from the chamber to control the pressure therein, and baffle means between the inlet and outlet arranged to direct oil flowing through the chamber toward the head or end wall to cool said wall.

5. In a device of the character described, a cylinder, a power piston in said cylinder including a head or end wall and side walls, ring grooves in the side walls, a pair of expandable rings in each groove, an oil chamber within the piston at the inner side of the head or end wall, pressure means operated by oil pressure in said chamber and so connected with the rings as to expand them against the cylinder walls and also to separate the rings in a groove to press them against the sides of the groove, a conduit connected with said chamber to conduct oil under pressure thereto, a nonreturn valve in said conduit adjacent the chamber, and an outlet valve connected with said chamber at a distance from

the inlet to cause circulation of oil through the chamber to cool the head or end wall and capable of restricting flow of the oil from the chamber to control the pressure therein.

6. A power piston of the character described including a head or end wall and side walls, a fluid chamber within the piston at the inner side of the head or end wall, a conduit connected to one side of the chamber to conduct fluid under pressure thereto, and a restricted outlet at the opposite side of the chamber comprising a spring closed valve arranged to open by pressure of the fluid to permit circulation of fluid through the chamber to control the temperature of the head or end wall while controlling the pressure in the chamber and to retain the fluid in the chamber until displaced by pressure fluid entering through the inlet conduit so as to maintain the chamber full of the fluid at all times.

7. A power piston of the character described including a head or end wall and side walls, a fluid chamber within the piston at the inner side of the head or end wall, a conduit connected to one side of the chamber to conduct fluid thereto, a restricted outlet at the opposite side of the chamber comprising a spring closed valve arranged to open by pressure of the fluid to permit the fluid to flow therethrough and control the temperature of the head or end wall while controlling the pressure in the chamber and to retain the fluid in the chamber until displaced by pressure fluid entering through the inlet conduit so as to maintain the chamber full of the fluid at all times, and transversely extending ribs on the inner side of said end wall projecting into the chamber to conduct heat from the end wall to the fluid and extending longitudinally of the general direction of flow of said fluid in the chamber.

8. A power piston of the character described including a head or end wall and side walls, a fluid chamber within the piston at the inner side of the head or end wall, a conduit connected to

one side of the chamber to conduct fluid thereto, a restricted outlet at the opposite side of the chamber comprising a spring closed valve arranged to open by pressure of the fluid to permit circulation of fluid through the chamber to control the temperature of the head or end wall while controlling the pressure in the chamber and to retain the fluid in the chamber until displaced by pressure fluid entering through the inlet conduit so as to maintain the chamber full of the fluid at all times, a baffle extending upwardly from the lower part of the chamber toward the head or end wall and spaced therefrom to direct fluid flowing through the chamber toward the head or end wall to control the temperature thereof, and ribs on the inner side of said end wall projecting into the chamber toward the baffle and arranged transverse to the baffle to conduct heat from the end wall to the fluid and extending longitudinally of the general direction of flow of said fluid through the chamber.
